CLAIM

The ornamental design for a sports glove with perforations in ventral surface, as shown and described.

DESCRIPTION

FIG. 1 is a front elevational view of my design in an unstretched condition, environmental structure herein being shown in phantom line and forming no part of my design; FIG. 2 is a front perspective view of the design shown in FIG. 1 as shown on a hand of a user in a stretched condition; FIG. 3 is a front elevational view of the design shown in FIG. 2; FIG. 4 is a right side elevational view of the design shown in FIG. 2; and, FIG. 5 is a left side elevational view of the design shown in FIG. 2. The broken line showing of a the back side of the glove is for illustrative purposes only and forms no part of the claimed design.
